United States Patent

Des. 236,094
Patented July 29, 1975

236,094

SMOKE AND GAS DETECTOR

Carlton Swain Moorefield, 4935 Birch Lane,
Alexandria, Va. 22308

Filed Apr. 5, 1974, Ser. No. 458,323

Term of patent 14 years

Int. Cl. D10—06

U.S. Cl. D10—106

FIG. 1

FIG. 2

FIG. 3

FIG. 4

FIG. 1 is a front view of a smoke and gas detector showing my new design;

FIG. 2 is a rear view of the design of FIG. 1;

FIG. 3 is a plan view of the design of FIG. 1; and

FIG. 4 is an end view of the design of FIG. 1.

The unseen bottom view of FIG. 1 is the same as the plan view of FIG. 3.

Both of the ends are as shown in FIG. 4.

I claim:

The ornamental design for a smoke and gas detector, as shown and described.
